UNITED STATES PATENT OFFICE

159,350

INFANT'S DISH

Clifford S. La Tour, Chicago, Ill., assignor to Lynn Chicago Corporation, Chicago, Ill., a corporation of Illinois

Application December 11, 1948, Serial No. 150,103

Term of patent 14 years

(Cl. D44—15)

To all whom it may concern:

Be it known that I, Clifford S. La Tour, a citizen of the United States, and residing in Chicago, in the county of Cook and State of Illinois, have invented a new, original, and ornamental Design for an Infant's Dish, of which the following is a specification, reference being had to the accompanying drawings, forming part thereof.

Fig. 1 is a perspective view of an infant's dish showing my new design;

Figs. 2 and 3 are respectively rear and front elevational views;

Fig. 4 is an end elevational view; and

Figs. 5 and 6 are vertical sectional views taken respectively on lines 5—5 and 6—6 of Fig. 1.

I claim:

The ornamental design for an infant's dish, substantially as shown.

CLIFFORD S. LA TOUR.
